Application September 10, 1949, Serial No. 114,955

8 Claims. (Cl. 250—33.67)

1

This invention relates generally to antennas for use in the very high frequency range and more particularly to antennas which are responsive over a plurality of bands in the very high frequency range without individually tuning or orienting for the various channels in the frequency bands.

Television communication is presently carried on in two separate frequency bands in the very high frequency range. These bands are generally referred to as the low television band and the high television band with the low band including frequencies from 54 to 72 megacycles and 76 to 88 megacycles and the high band covering frequencies from 174 to 216 megacycles. The low band therefore actually includes two separate frequency ranges and extends over 34 megacycles which is a very large percent of the average frequency of the low band. It is very difficult to provide a single antenna system having high response over the entire range of the low band and which is also effective throughout the high frequency band.

Most presently used systems provide separate antenna elements which are of such configuration to provide optimum response in the two bands. These systems have been large and bulky and have not generally been suitable for indoor installation and particularly cannot be enclosed in the receiver cabinet. Other antennas have been used in which the antenna elements are adjustable so that the length can be made an optimum value for the station being received. This is undesirable as it is necessary to make adjustment of the antenna elements each time the receiver is tuned to a different station. These available antenna systems are also directional in their characteristics and when the same antenna elements are used for receiving a plurality of stations, the position of the elements must be adjusted for the various stations or a compromise must be made so that the response is not optimum for all of the channels.

It is therefore an object of the present invention to provide an improved antenna system for operation on two separate frequency bands each of which includes a relatively wide range of frequencies.

A further object of this invention is to provide a small antenna which can be enclosed in a receiver cabinet and which provides efficient signal pickup on a plurality of channels in a wide range of frequencies without tuning or orienting the antenna for the individual channels.

Another object of this invention is to provide

2

tuning means for an antenna which is naturally responsive in one range of frequencies for tuning the antenna to provide reception of a wide band of lower frequencies without substantial loss of power.

A feature of this invention is the provision of tuning means for antennas of either the inductive or capacitive type in which an element having reactance of opposite sense to that of the antenna is coupled to the antenna for tuning the same for operation at lower frequencies with minimum power loss.

A further feature of this invention is the provision of an antenna system having reactive signal collecting means of such dimensions to provide efficient pickup at high frequencies and reactive tuning means coupled to the collecting means for tuning the system for operation at lower frequencies, with one of said reactive means being inductive and the other capacitive, and with a circuit coupled to the inductive means providing a double resonant circuit to increase the band width of the antenna at the lower frequencies.

Another feature of this invention is the provision of a loop antenna having such dimensions to provide efficient pickup at frequencies in one frequency band and capacitive means coupled to the loop for tuning the loop for efficient pickup at frequencies in a lower frequency band, with resonant circuits coupled to the loop to provide double resonance in both frequency bands to increase the frequency range over which efficient signal pickup is obtained.

Still another feature of this invention is the provision of loop antenna systems including tuning means for providing efficient pickup over two separate frequency bands, with a plurality of systems being coupled together to provide increased received power.

A still further feature of this invention is the provision of a dipole antenna system having the arms thereof dimensioned to provide efficient pickup at relatively high frequencies and inductive tuning means for the dipole to provide efficient pickup in a band of lower frequencies, with a reactive circuit coupled to said inductive tuning means to provide double resonance in the band of lower frequencies to increase the response throughout this band.

Further objects, features and advantages will be apparent from a consideration of the following description taken in connection with the accompanying drawings, in which:

Fig. 1 illustrates a tuned loop antenna;

Fig. 2 illustrates a tuned dipole antenna; Figs. 3 and 4 schematically illustrate antenna systems having double resonant tuned circuits; Fig. 5 is a curve chart showing the low frequency response of the system in accordance with the invention;

Fig. 6 illustrates a loop antenna constructed in accordance with the invention;

Figs. 7 and 8 are schematic diagrams of the loop antenna of Fig. 6.

Fig. 9 illustrates the high frequency response of the antenna of Fig. 6;

Fig. 10 illustrates a dipole antenna constructed in accordance with the invention; and

Figs. 11 and 12 illustrate the coupling of a plurality of tuned antenna systems.

In practicing the invention, antennas of the loop or dipole type are constructed of such dimensions to provide efficient signal pickup in the high frequency television band. Tuning systems are provided for the antennas to provide efficient operation in the low frequency television band. It has been found that for an inductive (loop) antenna the tuning should be done entirely by capacity, and for a capacitive antenna (dipole) the tuning should be done entirely by inductance. The tuning is arranged to provide maximum response near the center of the low frequency band with the response obtained by the main tuning element providing efficient pickup over only a central portion of the band. A tuned circuit is then coupled to the inductive element (either the loop antenna or the tuning means for the dipole) to provide double resonance in the low frequency band so that the band width is increased and efficient pickup is provided over the entire low frequency band. A plurality of antenna elements may be coupled together to provide increased pickup power.

Referring now to the drawings, in Fig. 1 there is illustrated a loop antenna 10 with tuning means 11 coupled thereto. The sides of the loop have a length substantially equal to one quarter of a wave length in the high frequency band to provide good response in the high band. This provides an antenna of a size which can be conveniently provided within a television receiver cabinet. The tuning means is provided for tuning the antenna to provide efficient pickup in the low frequency band. The tuning means 11 is shown schematically to include capacitance 12 and inductance 13. It is known that tuning can be obtained by various combinations of capacity and/or inductance to provide maximum response over a desired frequency range. The optimum power which can be obtained from an antenna varies directly with the square of the signal available and varies inversely with the band width. However, when tuning means are coupled to antennas the power derived by such antennas may be considerably reduced. When using an inductive antenna such as the loop 10 of Fig. 1, with tuning means as indicated at 11, the resulting power is governed by the following formula:

$$P = P_0 \times \frac{L_2}{L_1 + L_2}$$

In the above formula P is the power available from the antenna, P_0 is the optimum power obtainable, L_1 is the inductance of the loop and L_2 is the inductance of the tuning means. It is apparent from the above that for maximum derived power L_2 should be infinite. Therefore an inductance should not be used in the tuning unit

11 for tuning the loop and capacity only should be used for tuning an inductance antenna.

The above considerations also apply to a dipole antenna such as shown in Fig. 2. In this figure a dipole antenna 15 is illustrated having arms 16 and 17 which are connected to a tuning unit 18. This tuning unit is also illustrated as including inductance 19 and capacity 20. The antenna elements are of such dimensions to provide efficient pickup at one frequency as for example the high television band and the tuning unit 18 may be used for tuning the system for operation at a lower frequency. The optimum power from the dipole is governed by the same factors as the loop, that is the power varies directly as the square of the signal and inversely as the band width. The power which may be derived from the antenna is again reduced by the use of tuning means with the power available being indicated by the following formula:

$$P = P_0 \times \frac{C_1}{C_1 + C_2}$$

In this formula C_1 is the capacity of the dipole antenna and C_2 is the tuning capacity across the dipole. It is apparent from this formula that for a minimum power loss C_2 should be zero. Therefore for capacitive antennas, such as dipoles, the tuning should be done entirely by an inductance.

It is apparent from the above that in either a loop or dipole system which is tuned to provide maximum response at a frequency below the natural frequency of the antenna, the system can be represented as a condenser and inductor in series with the voltage picked up. This is shown in Fig. 3 in which 25 indicates signal voltage, 26 the condenser, and 27 the inductance. In the case of a loop antenna, 21 is the inductance of the loop and 26 is the tuning condenser. In the case of a dipole antenna, 26 is the capacity of the dipole and 27 is the tuning inductor. As shown by the basic power formula, the power varies inversely with band width and if the tuning is such that the complete low frequency band is provided, the power will be substantially reduced. It has been found that increased power can be obtained by tuning the antenna system for optimum pickup over only a portion of the band and increasing the band width by the use of another tuned circuit coupled to the antenna system. This secondary circuit may be most easily applied to the inductive element of the antenna system and provides a double tuned circuit which equalizes the response over the desired band. This is illustrated in Fig. 3 in which the condenser 28 and inductance 29 are coupled to the inductance 27 of the primary antenna circuit. The secondary circuit is coupled to a critical fraction of the inductance 27 to provide the desired overall response. The output impedance is symbolized by resistor 30 and the ratio of the inductance 27 to the capacity of the condenser 28 may be such that the impedance is 300 ohms to match the standard balanced line, as used for connecting the antenna system to the receiver with which it is used.

In Fig. 5 there is illustrated the response curves of the system illustrated in Fig. 3. Curve A shows the response provided by the main tuning elements, that is the tuning condenser of the loop or the tuning inductor of the dipole. Curve B shows the response curve when the secondary or equalizing circuit is used to provide a double response which broadens the band to cover the

entire low frequency television band. It is to be noted that the maximum pickup obtained with the secondary circuit is not substantially less than the pickup obtained by the single resonant system, and the average gain over the entire low frequency band is more uniform than that obtained by a single resonant system. This circuit therefore acts as an equalizer.

In Fig. 4, there is illustrated a schematic circuit generally similar to that of Fig. 3 with the antenna system being represented by signal voltage 25, capacitor 26 and inductance 27 in series. The secondary circuit or equalizer of Fig. 3 is replaced by a balanced circuit including condensers 31 and 32 and inductor 33 so that a balanced output is provided to match the balanced input of standard television receivers. The secondary circuit is tuned to the same frequency as the primary antenna circuit and the ratio of inductance to capacity of the secondary circuit is adjusted to provide the desired output impedance.

In Fig. 6, there is illustrated a structural embodiment of a loop antenna system in accordance with the invention. The antenna is provided on an insulating board 40 on which the conducting elements 41 and 42, which form the loop, are supported. The V-shaped elements 41 and 42 have sides 43, 44, 45 and 46 which are of a length substantially equal to one quarter of a wave length in the high frequency band. For operation in the high television band, around 200 megacycles, the length of each side of each of the elements should be about 14 inches. The two elements 41 and 42 are interconnected by balanced transmission lines 47 and 48, the conductors of which are transposed at the center so that a continuous circuit is provided through the conducting elements 41 and 42 and through the transmission lines 47 and 48. The width of the conducting elements is selected to provide the desired loop inductance and distributed capacity for the frequencies involved. A conducting strip 49 may be provided on the insulating board 40 connecting the corners of the conducting elements 41 and 42, so that these points are maintained at a reference potential.

For tuning the loop antenna of Fig. 6 for operation in the low frequency band, capacitor 51 is provided. An inductor 52 is connected in series with the capacitor 51 but the value of the inductor 52 is such that it has little effect for low band operation. The purpose of this inductor will be described in connection with the high band operation. Capacitor 51 is connected across the common connection between the conductors in the transmission lines 47 and 48. The value of the condenser is related to the inductance of the loop to provide a single tuned circuit having maximum response in the center of the low frequency band. To increase the band width of the response a double tuned circuit is provided by adding a secondary circuit, or equalizer, across the loop. This is accomplished by the condensers 53 and 54 and inductor 55 which are connected to the adjacent ends of the sides 43 and 46 of the loop.

For a better understanding of the operation of the loop in the low frequency band, reference is made to Fig. 7 in which the various elements of the loop are represented by equivalent circuit elements. L_{43} , L_{44} , L_{45} and L_{46} represent the inductances of the sides 43, 44, 45 and 46, respectively of the loop. L_{56} , L_{57} , L_{58} and L_{59} represent the inductances of the conductor 56 and 57 of the

transmission line 47 and the conductors 59 and 60 of the transmission line 48. It is therefore seen that resonant circuits are provided including the loop portions in which the received signal is induced. The signal induced in the loop is represented by the generator symbols 58 in series with each side of the loop. The signals induced in all of the sides are added so that the total signal is four times that induced in each 10 loop side. As previously stated, the condenser tunes the resonant circuits to the center of the low frequency band and the output thereof would be such as shown in curve A of Fig. 5. The secondary circuit is connected across a portion of the inductance of the loop circuits, being connected across inductances L_{43} and L_{46} . At the frequencies involved the strip 49 at reference potential may be assumed to have no impedance so that in effect the sides 43 and 46 of the loop are directly connected in series. The condensers 53 and 54 and inductor 55 provide a double tuned circuit which produces a response as indicated in curve B of Fig. 5. The output is taken off 20 across inductor 55 as indicated by resistor R300. It is well known that to provide a double tuned circuit the two branches must be tuned to the same frequency. That is, the primary circuit including the inductances of the sides of the loops and the conductors of the transmission lines and the capacity of condenser 51 must be tuned to the same frequency as the secondary circuit including condensers 53 and 54 and inductor 55. The coupling inductances L_{43} and L_{46} must have the value to provide the desired band width. 25 Also the ratio of inductance to capacity of the secondary circuit determines the load impedance. To provide satisfactory tuning over the low frequency television band (54 to 88 megacycles) the following values were used:

40 Loop sides 43, 44, 45 and 46 14 inches along edges, 2 inches wide.
41 Transmission lines 47 and 48 11 inches long.
42 Condenser 51 6 micromicrofarads.
43 Inductor 52 0.07 microhenry.
44 Condensers 53 and 54 18 micromicrofarads.
45 Inductor 55 0.5 microhenry.

50 It is to be pointed out that these values are merely representative and other values may provide satisfactory operation.

For an explanation of the operation of the loop on the high frequency band, reference is 55 made to Fig. 8. As previously stated, the sides of the loop have a length substantially equal to one quarter of a wave length in the high frequency band. More specifically, the length may be equal to one quarter of a wave length in the center of the band which, in the high television band, is about 195 megacycles. At this frequency, the capacitor 51 and the inductance 52 become in effect a relatively large capacity and form a low impedance between the conductors of the 60 transmission lines 47 and 48. This has the effect of a short circuit so that the transmission lines 47 and 48 become shorted stubs. The length of these lines 47 and 48 is selected so that the effective electrical length thereof is one quarter of a wave length. Each of the conducting elements 41 and 42 forms, in effect, a half wave dipole for high frequency operation. The transmission line 48 connects the conducting elements 41 and 42 in series so that the signals therefrom are added in phase to provide high gain. The response of 65

the antenna in the high band is indicated by the curve C in Fig. 9.

Although the gain of the antenna is very high in the high frequency band, it may be desirable to make the gain throughout the band more uniform. This may be accomplished by the provision of a secondary or equalizer circuit represented in Fig. 8 by the inductors 80 and 81 and the condenser 82. For operation in the band from 174 to 216 megacycles, the inductors 80 and 81 should have values of the order of 0.005 microhenry and the condenser 82 should have a value of the order of 4 micromicrofarads. This secondary circuit is ineffective when operating on the low band because the inductors 80 and 81 would be negligible and the impedance of the condenser 82 would be very large. Similarly, the secondary circuit for low band operation is ineffective when operating in the high frequency band as the capacitors 53 and 54 become substantially short circuits and the impedance of the inductors 55 is relatively high. The double tuned response is shown in curve D, Fig. 9.

In Fig. 10 there is illustrated a dipole antenna system embodying the invention. The dipole elements 62 and 63 may be provided on any suitable insulating support and may have increased widths as they extend away from each other to provide better response over a relatively wide range of frequencies. The antenna elements are of such dimensions that the antenna will provide efficient pickup at the highest frequency in the high frequency band. If it is desired to mount such an antenna in a receiver cabinet, the ends of the elements may be bent at right angles to conserve space. The bent down ends load the antenna and the response thereof is not substantially reduced. The dipole antenna is tuned by an inductance formed by a section 64 of 300 ohm transmission line connected to the dipole elements 62 and 63. The conductors in the transmission line 64 are connected together at the end 65 removed from the dipole arms to form a continuous circuit. The line 64 is of such length that the inductance thereof is of the proper value for tuning the dipole antenna to the center of the low frequency band. Coupled to the transmission line 64 is a secondary circuit or equalizer including condensers 66 and 67 and inductor 68. The equalizer operates in the same manner as fully described in connection with Fig. 6 to provide a uniform response over the low band and to provide a 300 ohm output impedance so that standard 300 ohm balanced line can be used to connect the antenna to a television receiver.

For operation on the television bands referred to, a satisfactory dipole antenna was constructed having an equivalent capacity of the order of 15 micromicrofarads. The stub was a 12 inch length of 300 ohm line with the secondary circuit being connected about 5 inches from the dipole. The condensers 66 and 67 were 20 micromicrofarads each and the inductor 68 was .7 microhenry.

In Figs. 11 and 12 there are illustrated arrangements for connecting a plurality of loop antennas such as disclosed in Fig. 6 together to form an array. In Fig. 11 the two antennas 70 and 71 are connected in parallel to a single equalizer including condensers 72 and 73 and inductor 74. For operation with loops as described, the condensers 72 and 73 should have a value of about 18 micromicrofarads and the inductor 74 should have a value of the order of 1 microhenry. It is essential that the loops be oriented in the same

manner and that the lines connecting the loops to the equalizer have equal lengths so that the signals are exactly in-phase. It may be desirable to make one of the tuning condensers 51 variable so that the two loops can be accurately tuned to the same frequency. Similarly in Fig. 12 three loops 75, 76 and 77 are connected in parallel and again, the lines connecting the loops to the equalizer circuit must be of equal length.

It is seen from the above that antenna systems of both the loop and dipole type have been provided, which produce high gain over two spaced frequency bands. By the use of double tuned circuits relatively wide band widths are obtained in both bands. These antennas are of such size that they can be enclosed in a television receiver cabinet so that separate installation is not required. Alternatively the antennas may be used for outdoor or attic installations. For such installation it may be desirable to provide two separate antennas for the two bands, with the antenna for the high frequency band being as illustrated in Fig. 6, and the antenna in the low frequency band having such dimensions that the sides of the loop have a length substantially equal to a quarter wave in the low frequency band.

Although certain embodiments of the invention have been described which are illustrative thereof, various changes and modifications can be made therein without departing from the intended scope of the invention as defined in the appended claims.

I claim:

1. An antenna system for operation in a first frequency band and in a second frequency band of lower frequency than said first band, with each of said bands covering a relatively wide range of frequencies, said system including a pair of V-shaped members positioned to form a square loop, said members being formed of relatively wide strips of conducting material with each side thereof having a length substantially equal to one quarter of a wave length at a frequency within said first frequency band, a transmission line including a pair of spaced conductors connected to the ends of said members, said transmission line having the conductors thereof transposed so that a continuous series circuit is provided through said members and said conductors of said transmission line, and tuning means coupled to said transmission line at substantially the center thereof for tuning said antenna system for operation in said second frequency band, said tuning means providing a low impedance between the conductors of said transmission line at frequencies in said first frequency band.

2. An antenna system for operation in a first frequency band and in a second frequency band of lower frequency than said first band, with each of said bands covering a relatively wide range of frequencies, said system including a pair of V-shaped members positioned to form a square, said members being made of relatively wide strips of conducting material with each side thereof having a length substantially equal to one quarter of a wave length at a frequency within said first frequency band, a transmission line including a pair of spaced conductors connected to the ends of said members, said transmission line having the conductors thereof transposed so that a continuous series circuit is provided through said members and said conductors of said transmission line, condenser means coupled to said transmission line for tuning said an-

tenna system for operation in said second frequency band, and a circuit coupled to adjacent ends of said members providing a double tuned circuit for increasing the response of said antenna system over a wide range of frequencies in said second frequency band.

3. An antenna system for operation in a first frequency band and in a second frequency band of lower frequency than said first band, with each of said bands covering a relatively wide range of frequencies, said system including a pair of V-shaped members positioned to form a square loop, said members being formed of relatively wide strips of conducting material with each side thereof having a length substantially equal to one quarter of a wave length at a frequency within said first frequency band, a transmission line including a pair of spaced conductors connected to the ends of said members, said transmission line having the conductors thereof transposed so that a continuous series circuit is provided through said members and said conductors of said transmission line, tuning means coupled to said transmission line at substantially the center thereof for tuning said antenna system for operation in said second frequency band, said tuning means providing a low impedance between the conductors of said transmission line at frequencies in said first frequency band, and a circuit coupled to adjacent ends of said members providing a double tuned circuit for increasing the response of said antenna system over a wide range of frequencies in said second frequency band.

4. An antenna system for operation in a first frequency band and in a second frequency band of lower frequency than said first band, with each of said bands covering a relatively wide range of frequencies, said system including a pair of V-shaped members positioned to form a square loop, said members being formed of relatively wide strips of conducting material with each side thereof having a length substantially equal to one quarter of a wave length at a first frequency within said first frequency band, a transmission line including a pair of spaced conductors connected to the ends of said members, said transmission line having an electrical length substantially equal to one half of a wave length at said first frequency, said conductors being transposed and being connected to said members in such manner that a continuous series circuit is provided through said members and said conductors, and tuning means coupled to said transmission line at substantially the center thereof for tuning said antenna system to a frequency within said second frequency band, said tuning means providing a low impedance between said conductors of said transmission line at frequencies in said first frequency band so that a portion of said transmission line forms a quarter wave shorted stub connecting said V-shaped members in series.

5. An antenna system for operation in a first frequency band and in a second frequency band of lower frequency than said first band, with each of said bands covering a relatively wide range of frequencies, said system including a pair of V-shaped members positioned to form a square loop, said members being formed of relatively wide strips of conducting material with each side thereof having a length substantially equal to one quarter of a wave length at a first frequency within said first frequency band, a transmission line including a pair of spaced con-

5

10

ductors connected to the ends of said members, said transmission line having an electrical length substantially equal to one half of a wave length at said first frequency, said conductors being transposed and being connected to said members in such manner that a continuous series circuit is provided through said members and said conductors, a conducting strip connecting the apexes of said members to hold the same at a reference potential, a first circuit including a condenser and an inductor connected between said conductors of said transmission line at substantially the center thereof, said circuit tuning said antenna system to a second frequency within said second frequency band, and a second circuit resonant at said second frequency coupled to adjacent ends of said members providing a double tuned circuit having a substantially uniform response over the entire range of frequencies in said second frequency band, said first circuit having a low impedance at frequencies in said first frequency band so that a portion of said transmission line forms a quarter wave shorted stub connecting said V-shaped members in series.

6. An antenna system for operation in a frequency band covering a relatively wide range of frequencies including, a pair of V-shaped conducting members positioned to form a square loop, with each side thereof having a length substantially equal to one-quarter of a wavelength and a frequency within said frequency band, a transmission line including a pair of spaced conductors connected to the ends of said members, said transmission line forming quarter-wave shortage stubs connecting said V-shaped members in series, and a resonant circuit tuned to said frequency within said frequency band coupled to adjacent ends of said members for providing a double tuned circuit so that the response of said antenna system over said wide range of frequencies is increased.

7. An antenna system for operation in a first frequency band and in a second frequency band of lower frequency than said first band, with each of said bands covering a relatively wide range of frequencies, said systems including in combination, a pair of V-shaped members positioned to form a square, said members being made of relatively wide strips of conducting material with each side thereof having a length substantially equal to one quarter of a wave length at a frequency within said first frequency band, a transmission line including a pair of spaced conductors connected to the ends of said members, said transmission line having the conductors thereof transposed so that a continuous series circuit is provided through said members and said conductors of said transmission line, condenser means coupled to said transmission line for tuning said antenna system for operation in said second frequency band, and resonant circuit means coupled to adjacent ends of said members including a first portion resonant in said first frequency band and providing a first double tuned circuit for increasing the response of said antenna system over a wide range of frequencies in said first frequency band, said resonant circuit means including a second portion resonant in said second frequency band providing a double tuned circuit for increasing the response of said antenna system over a wide range of frequencies in said second frequency band.

8. An antenna system for operating in a first frequency band and in a second frequency band of lower frequency than said first band with each

75

11

of said bands covering a relatively wide range of frequencies, said system including in combination, first and second elongated conductor portions having relatively low inductance and each having a length substantially equal to one-half wave length in the higher of said frequency bands, said conductor portions being shaped and positioned to form a loop with the ends of each portion being adjacent the ends of the other portion, a balanced two conductor transmission line connected at each end to adjacent ends of said first and second conductor portions with the conductors thereof being transposed so that a continuous series circuit is provided through said members and said conductors of said transmission line, tuning means coupled to said transmission line at substantially the center thereof for tuning said antenna system for operation in said second frequency band, said tuning means providing a low impedance between the conductors of said transmission line at frequencies in said first frequency band, and a circuit coupled to adjacent ends of said first and second conductor portions providing a double tuned cir-
